UNITED STATES PATENT OFFICE.

WILLIAM S. RICHARDSON, OF CANTON, MASSACHUSETTS, ASSIGNOR TO UNITED STATES FASTENER COMPANY, A CORPORATION OF MAINE.

SNAP-FASTENER SOCKET.

1,240,878.

Specification of Letters Patent. Patented Sept. 25, 1917.

Application filed May 9, 1917. Serial No. 167,458.

To all whom it may concern:

Be it known that I, WILLIAM S. RICHARDSON, a citizen of the United States, residing in Canton, in the county of Norfolk and 5 State of Massachusetts, have invented an Improvement in Snap-Fastener Sockets, of which the following description, in connection with the accompanying drawings, is a specification, like letters on the drawings 10 representing like parts.

This invention relates to a socket member of a stud and socket fastener such as is commonly used for gloves and other garments, and the invention consists in certain 15 improvements in construction which will be hereinafter pointed out.

In the accompanying drawing, Figure 1 is a plan view of the blank from which the main portion of the socket member of the 20 fastener is produced; Fig. 2 is a plan view of the blank for another portion of the fastener; Fig. 3 is a plan view of the complete fastener socket ready to be attached to the fabric; Fig. 4 is a longitudinal section there- 25 of; and Fig. 5 is a longitudinal section showing the fastener attached to the fabric.

The main portion of the socket member is made from a blank such as represented in Fig. 1 of substantially cross shape, having 30 the projecting arms *a* and central portion *b* uniting said arms, and portions *d* at the ends of said arms in substantially the shape of a sector of a circular annulus.

The blank is provided with notches *e* sub- 35 stantly at the junction of the arms *a* with the sectors *d*, and the blank of the form shown in Fig. 1 is then drawn to the form shown in Figs. 3 and 4, in which the said arms *a* are brought into substantial contact 40 with one another and form a tubular body portion which is closed at one end by the connecting part *b*, while the parts *d* at the other end form a foot or flange extending outwardly from the tubular body portion *a*.

45 A rounding bead *f* is also formed at the junction of the body and foot portions *a* and *d*, making a somewhat contracted mouth or entrance opening into the tubular body portion *a*.

50 As a protection and reinforcement for the foot portion *d*, a plate *g* is provided as

shown in Fig. 2, in the form of a disk, the outer circumference of which is of substantially the same diameter as that of the foot portion *d* of the fastener and socket shown 55 in Fig. 3 while the inner periphery of the annular disk affords an opening of proper size to surround the bead *f* at the entrance to the socket member, and is provided with four inwardly projecting portions *g*².

In forming the blank shown in Fig. 1 to the form shown in Fig. 4, the notches *e* in the blank will come together and form small openings through the foot portion *d* adjacent to the bead *f*, as best shown in Fig. 3. 60

The inward projections *g*² of this plate *g* are properly located to correspond to these openings, and by first turning the said projections *g*² at right angles to the plate *g* they may be passed through the openings *e* 70 in the main portion of the fastener, after which they may be turned down parallel to the remainder of the plate *g* and over the foot portion *d* as shown in Figs. 3 and 4 thereby securely fastening the plate *g* to the 75 foot of the main portion of the fastener so that it covers the lines of separation between the sectors of the foot *d* and affords a finish for the foot of the fastener when applied to the fabric as shown in Fig. 5. 80

When applying a fastener to the fabric *i*, Fig. 5, the tubular body portion *a* of the fastener socket, when in the form shown in Fig. 4, is passed through a hole in the fabric so that the foot portion *d* comes against one 85 surface of the fabric. A cap *k* having an in-turned flange *k*² is then applied over the closed end *b* of the main portion of the socket at the other side of the fabric and is pressed toward the fabric and toward the 90 foot *d*, *g*, of the socket at the other side of the fabric. Such pressure causes the tubular portion *a* to collapse endwise and expend circumferentially as shown in Fig. 5 so that it engages the in-turned flange *k*² of the cap 95 *k* and clenches the entire socket to the fabric *i* which lies between the cap *k* and the foot *d*, *g*, of the socket member.

What I claim is:

A socket member for a snap fastener comprising a tubular body portion closed at one end, and provided with an outwardly ex-

tending flange or foot around the other end; said body and foot portions comprising separate abutting sections, and being provided with a number of openings through said foot
5 in proximity to the junction thereof with the tubular body portion; an annular foot plate having at its inner periphery projecting

portions which are passed through the said openings in the foot and engage with said foot to secure the said base plate thereto.

10

In testimony whereof, I have signed my name to this specification.

WILLIAM S. RICHARDSON
